US0D1086762S

(12) **United States Design Patent** (10) Patent No.: **US D1,086,762 S**
(45) Date of Patent: ** Aug. 5, 2025

(54) **VIRTUAL REALITY GOGGLES HOLDER**

(71) Applicant: **Juzhen Wen**, Meizhou (CN)

(72) Inventor: **Juzhen Wen**, Meizhou (CN)

(**) Term: **15 Years**

(21) Appl. No.: **29/822,421**

(22) Filed: **Jan. 9, 2022**

(51) LOC (15) Cl. **06-04**

(52) U.S. Cl.

USPC **D6/682; D14/224.1**

(58) **Field of Classification Search**

USPC D6/672, 682, 682.1, 682.2, 682.3, 682.4, D6/682.5; D14/224, 224.1, 203.8, 209.1, D14/238.1, 251, 451

CPC .. H04R 1/02; H04R 1/10; A47G 29/08; G06F 1/16
